COMBINATION FLOOR AND TUB TOWEL RACKS

George B. Bentz, New York, N. Y.

Application June 7, 1938, Serial No. 212,361

2 Claims. (Cl. 211—86)

The invention aims to provide a new and improved rack for towels and the like adapted primarily for use in bathrooms, the rack being of such construction that it may be supported on one wall of a bathtub in a rather small bathroom, or may rest directly on the floor in more commodious quarters.

With the foregoing in view, the invention resides in the novel subject matter hereinafter described and claimed, description being accompanied by reference to the accompanying drawings.

Fig. 1 is a perspective view showing one form of the invention.

Fig. 2 is a transverse sectional view through a portion of one side wall of a double-wall bathtub showing the rack of Fig. 1 positioned thereon.

Fig. 3 is a view similar to Fig. 2 but showing the rack in place on a rolled-rim tub wall.

Fig. 4 is an end elevation of the rack showing it resting upon the floor.

Fig. 5 is a fragmentary perspective view of a portion of the pivoted holding arm shown in the preceding figures.

Fig. 6 is a perspective view showing another form of construction.

Fig. 7 is a perspective view showing a still further form of construction.

Fig. 8 is an end elevation showing a construction in which the tub-wall-straddling arches are formed from spring metal to yieldably grip the wall.

Fig. 9 is a perspective view showing a still further variation.

Figs. 10, 11, 12, 13 and 14 are perspective views showing still further forms of construction.

Fig. 15 is a perspective view showing a rack engaged with a kitchen sink for holding tea towels, dish cloths and the like.

In all forms of construction, the rack includes two horizontally spaced vertically elongated end frames constructed to either rest upon a floor or to straddle a bathtub side wall, and one or more horizontal rods extending between and secured to the upper portions of said end frames for use in hanging towels or other articles. The device may thus be used either upon a tub side wall or resting directly on the floor, according to the available space or the user's desire.

In the form of construction shown in Figs. 1 to 5, the two end frames are denoted at E. Each of these end frames includes an arch portion 15 having inner and outer legs 16 and 17 for disposition at the inner and outer sides of a double-wall tub 18 (Fig. 2) or an old type rolled-rim

tub 19 (Fig. 3). Projecting upwardly from each arch portion 15, preferably substantially continuous with the outer leg 17 thereof, is a rod-supporting post 20, the upper portion of said post being directed laterally from the plane of said leg 17. Supporting rods 21 for towels or other articles, extend between the two posts 20 and are secured thereto in any preferred manner. In the present showing, these posts are provided with apertured lugs 22 in which said rods are secured. I have also shown a grab rail or similar rod 23 extending between the legs 16 and suitably secured thereto, for instance by fastening their ends in lateral lugs 24 on said legs.

If desired, a vanity tray 25 may extend between the two end frames E and be suitably secured thereto. I may also mount a mirror 26 on the tray or upon one of the rods 21, if desired.

Pivoted to the leg 11 of each frame E, is a swingable arm 27 which occupies the vertically hanging position of Fig. 2 when the rack is upon a double-wall tub, occupies a substantially horizontal position (Fig. 3) when the rack is supported on a rolled-rim tub, and projects laterally from the leg 17 under the laterally directed post 20 (Fig. 4) when the rack is supported upon the floor. When the arm 27 is in either of the positions shown in Figs. 2 and 3, it abuts the tub wall to clamp the rack in place thereon, and when said arm is in the position of Fig. 4, the rack cannot tilt toward said arm due to a stop 28 on said arm which then abuts the leg 17.

The arm 27 is provided with an oblique slot 29 through which the arm pivot 30 passes, and at one end of said slot, said arm is formed with a notch 31. When the arm is in the position of Fig. 2, its weight causes it to descend with respect to the pivot 30, and the oblique slot 29 then causes said arm to move inwardly into tight contact with the tub wall. If desired, the pivot 30 may be in the form of a bolt and it may be tightened if desired to hold the arm 27 in this position. The lower end of the arm is preferably provided with a cushion 32 of rubber or the like to prevent it from injuring the enamel on the tub wall when it swings downwardly.

When the arm 27 is in the position of Fig. 5 or in that of Fig. 4, the notch 31 receives the pivot 30 and if this pivot be in the form of a bolt, it may be tightened if desired to lock the arm in place.

In Fig. 6, the end frames E' each comprise an arch 33 capable of straddling a tub wall, a horizontal rod portion 34 projecting laterally outward from one leg 35 of said arch, one vertical rod

36 extending upwardly from the rod portion 34, another vertical rod 37 extending upwardly from the arch 33, and a portion 38 connecting the upper ends of said rods 36 and 37. These portions 5 38 are connected by a plurality of rods 39 for supporting towels or the like. I have also shown the legs 40 of the two arches 33 integrally connected by another rod 41 which may constitute a grab rail or may be used simply as an additional support 10 for towels or the like.

I have shown a shelf 42 composed of a plurality of rods, extending between and secured to the end frames E¹, and have also illustrated a vanity tray 43 secured to said frames.

15 Any suitable provision may be made for holding the device of Fig. 6 in place upon a tub and for illustrative purposes, I have illustrated two pivoted arms 44 which extend about horizontally when the rack is upon a rolled-rim tub and hang 20 downwardly when said rack is mounted upon a double-wall tub.

In Fig. 7, the general structure is so similar to that disclosed in Fig. 1 that description of the features in common will not be necessary. 25 However, attention is invited to the slideable clamp members 45 on the inner legs 46 of the wall-straddling arches 47, which clamp members are simply slid downwardly into clamping position to hold the rack upon the tub wall. I also 30 draw attention to the rigid arms 48 which project laterally from the legs 49 of the arches 47 to engage the floor and prevent tilting of the rack when resting on the latter. The arms 48 are preferably connected by a rod 50, and floor-engaging feet 51 may be provided on said arms. The parts 52 are simply rubber buttons to prevent injury to the enameled surface of the tub wall.

In Fig. 8, it may be considered that the construction is substantially the same as that shown in Fig. 7. However, instead of using slideable clamp members such as 45, to secure the wall-straddling arches 52 in place, the arch legs 53 and 54 are formed from spring metal to yieldably grip the tub, the parts 55 being cushioned to prevent injury of the enamel. Due to the resilient nature of the legs 53 and 54, it is impracticable to provide a grab rail. Rigid arms 56 are provided, however, projecting laterally 45 from the legs 54 to aid in supporting the rack directly upon the floor.

In Fig. 9, the construction is almost identical with that shown in Fig. 7 but no grab rail is employed, and clamping screws 57 have been 55 shown threaded through the inner legs 58 of the wall-straddling arches 59 to secure them upon the tub, said screws having cushions 60 at their inner ends to prevent injuring the enamel. The other legs 61 of the arches 59 are also provided 60 with cushions 60' for the same purpose. 62, of course, illustrates a mirror, use of which is optional.

In Fig. 10, each end frame E² comprises spaced vertical rods 63 and 64, a rod portion 65 connecting the upper ends of said rods, and an arch formation 66 between the lower ends of said rods to straddle a tub wall. Small feet 67 may be secured to the lower extremities of the rods 63 and 64 if desired. Supporting rods 68 for towels 70 and the like extend between and are secured to the rod portions 65. I have also illustrated a shelf 69 composed of a plurality of rods extend-

ing between the lower portions of the side frames E² and suitably secured thereto.

In Fig. 11, the construction is very similar to that of Fig. 10 but the arches 70 are associated in a somewhat different manner with the rods 71 and 72 of the end frames E³.

In Fig. 12, the end frames E⁴ are practically identical with the end frames E¹ shown in Fig. 6. These end frames E⁴, however, are not connected by a shelf nor a vanity tray, but their upper portions are connected by towel-supporting rods 73 and their lower portions are connected by a grab rail or the like 74.

The construction shown in Fig. 13 is so similar to that illustrated in Fig. 6 that it will suffice 15 to state that a mirror 75 has been added and the grab rail omitted.

All of the tub-straddling arches shown in Figs. 10 to 13 are tapered to tightly wedge onto a wall 20 of a double-wall tub without requiring any fastening means, but if desired, suitable provision could be made for permitting these forms of construction also to be supported upon a rolled-rim tub.

In Fig. 14, the construction is very similar to 25 Fig. 13 but the mirror has been omitted and the legs 76 have been shortened.

In Fig. 15, a simplified rack is shown which may be of a relatively small size, if desired, for engagement with a kitchen sink 77. This rack 30 comprises two arches 78 to straddle the sink end wall, posts 79 secured to and projecting upwardly from said arches and having laterally curved upper ends 80, and towel supporting rods 81 extending between said curved ends and secured 35 thereto.

From the foregoing taken in connection with the accompanying drawings, it will be seen that novel and advantageous provision has been made for carrying out the objects of the invention, and while various preferred details have been shown, it is to be understood that the present disclosure is primarily for illustrative purposes, and that numerous variations may be made within the scope of the invention as 45 claimed.

I claim:

1. A towel rack comprising two horizontally spaced vertically elongated frames comprising a vertically elongated arch to straddle a tub wall 50 or rest on a floor, a horizontal rod portion projecting laterally from one leg of said arch, one vertical rod extending upwardly from the outer end of said horizontal rod portion, another vertical rod extending upwardly from the crown of 55 said arch, a connecting portion between the upper ends of said vertical rods, and horizontal rods extending between and secured to said connecting portions of the two frames.

2. A towel rack comprising two horizontally 60 spaced vertically elongated frames comprising a vertically elongated arch to straddle a tub wall, a horizontal rod portion projecting laterally from one leg of each arch, one vertical rod extending upwardly from the outer end of said horizontal 65 rod portion, another vertical rod extending upwardly from the crown of said arch, a connecting portion between the upper ends of said vertical rods, and a horizontal rod extending between and secured to said connecting portions 70 of the two frames.

GEORGE B. BENTZ.
